UNITED STATES PATENT OFFICE.

JOSEPH W. BROWER, OF INDIANAPOLIS, INDIANA.

COAL-OIL STOVE.

SPECIFICATION forming part of Letters Patent No. 271,215, dated January 30, 1883.

Application filed July 15, 1882. (No model.)

To all whom it may concern:

Be it known that I, JOSEPH W: BROWER, of Indianapolis, Indiana, have invented a new and useful Improvement in Coal-Oil Stoves, a description of which is as follows, reference being had to the accompanying drawings, in the several figures of which like letters indicate like parts.

My invention belongs to that class of stoves which are heated by coal-oil lamps; and it relates, first, to a safety-valve and condenser; second, to the top having inclined sides; third, to the flange or deflector around the base of the shell, and also to the various combinations of these as hereinafter set forth and claimed. My object is to produce a stove which shall be simple in construction, safe in use, and yet produce perfect combustion without heating the oil-reservoir, and to furnish an escape for any heated gas from the reservoir through a safety-valve.

In the drawings, Figure 1 represents a vertical section of my device; Fig. 2, a side view with a portion of the casing cut away, showing a longitudinal section of the burner; Fig. 3, a top view; Fig. 4, a top view of the burner and wick-tube; Fig. 5, a longitudinal section on the line *y y*, Fig. 4. Fig. 6 is a cross-section of wick-tube and inclosing-chamber.

My reservoir for oil is indicated by the letter D, and F is the opening for filling, which is closed by an ordinary screw-cap. Upon this is fixed a gas-chamber, C. The wick-tubes *f* are connected with this air-chamber, and the wicks *w* pass down through the gas-chamber into the reservoir. The sides of the wick-tubes are pierced with holes *e' e' e³*, and a larger opening, *e⁴*, is made in the wick-tube where it meets the top of the gas chamber. These openings allow the oil to escape which is drawn up after the lamp is blown out, and prevent its running over the top of the wick-tube. This oil settles and passes through these openings and other openings, *h h'*, and again meets the wick, and when the lamp is lighted will be the first oil drawn up and consumed. About the lower portion of the wick-tubes are fixed pyramidal chambers *b*, which have openings in the ends *d d' d² d³*, Fig. 5. These chambers allow air to pass through them, and serve to keep the wick-tubes cool, and to house the oil that drips

from the top of the wick-tubes or passes through the openings in the sides. The wicks are moved up and down by the ordinary toothed wheel, as shown. The wick-tubes and inclosing-chambers are surrounded by a screen or air-chamber, B.

a a' are the cones surrounding the flame when lighted, and are of the ordinary kind.

A is the shell or casing of the device, having 60 deflectors *g*, which throw all the heat to the central opening in the top. The sides of the top are inclined, as shown, *s s*, Fig. 1, and are jointed water-tight to the shell, so that the water and steam will be carried away to the 65 sides through suitable perforations located at the joint, and not be allowed to fall into the lamp. Shell A is hinged at K and latched at K' for convenience in use.

E is a safety-valve and condenser connected 70 by the pipe C' with the gas-chamber C, and having a return-pipe, C², connected with the oil-reservoir, for carrying thither the condensed vapors and oil that may be collected in the condenser. Any heated vapors or gases which 75 collect in the gas-chamber C will pass up the pipe C', and will either force up the cap E and escape into the air or will be collected and returned to the oil-reservoir by the pipe C².

My oil-reservoir is protected from heat by 80 the superimposed gas-chamber C and by the chambers about the wick-tubes, and the perforated wick-tubes allow the lamp to be blown out without driving the gases or heated vapors into the oil-reservoir or gas-chamber. 85 There is no puffing noise, no explosive return of gases forcing the wick up in the tube, no charring of the wick below the flame, and the lamp will stand and steadily burn where it is set by the wick-raising wheel. The perforated 90 screen B furnishes plenty of air and aids in keeping the lower parts cool. B² is a flange or deflector around the outside of the shell or case, to prevent smoke or vapor from rising, and also for drawing cold air in underneath. The 95 arrangement of my oil reservoir and gas-chamber has another advantage. The oil can never rise higher than the level of the opening F, and by placing this on the lower section, D, the oil can never enter the chamber C. The 100 deflectors *g g* throw the heat to the central opening, as I have said, and thus concentrate

its power, and a small or large vessel can be more easily heated than in stoves where deflectors are not used.

What I claim, and desire to secure by Letters Patent, is—

1. In a coal-oil stove, an oil-reservoir having a closed gas-chamber superimposed thereon, to the upper surface of which gas-chamber the wick-tubes are rigidly attached, in combination with a safety-valve attachment, substantially as described.
2. In a coal-oil stove, a safety-valve and condenser connected by a pipe with the gas-chamber and by a return-pipe with the oil-reservoir, substantially as described.
3. In a coal-oil stove, a closed gas-chamber superimposed upon an oil-reservoir and rigidly connected therewith, in combination with an air-screen which surrounds the wick-tubes, and means for conveying heated gases from the gas-chamber to the open air by means of a safety-valve, substantially as described.
4. In a coal-oil stove, a chimney or body having the top inclined from the central open-

ing to the sides, which are perforated at suitable intervals along the line of junction of the top and sides, which joint is made water-tight to carry away water and condensed steam, substantially as described.

5. In a coal-oil stove, an oil-reservoir, D, having an opening, F, a gas-chamber, C, superimposed thereon, in combination with the air screen or chamber B, the lamp-burner, and the shell A, having deflectors *g g*, and the top with inclined sides *s s*, substantially as described.

6. The combination of the oil-reservoir D, gas-chamber C, safety-valve E, with pipes C' C², and burner having perforated wick-tube *f*, and cooling-chamber *b*, with shell A, screen B, and flange B², substantially as described.

In witness whereof I have hereunto set my hand this 12th day of June, 1882.

JOSEPH W. BROWER.
